UNITED STATES PATENT OFFICE.

JOSEPH A. DAHLMAN, OF DULUTH, MINNESOTA.

GOLF CLUB.

Application filed April 7, 1925. Serial No. 21,335.

To all whom it may concern:

Be it known that I, JOSEPH A. DAHLMAN, a citizen of the United States, residing at Duluth, in the county of St. Louis and 5 State of Minnesota, have invented certain new and useful Improvements in Golf Clubs, which I do hereby declare the following to be a specification.

My invention relates to golf clubs, and 10 has for its object the provision of a club head of improved construction in which are weights so constructed, positioned and connected as to establish its proper balance and driving capacity. It has for a further object 15 the provision of weights provided with receptacles for fillers for increasing their gravity, or for shifting their centers of gravity to change the balance of the club head. It has for a further object the establishing 20 of the weights in the club head in such manner as to assure rigidity and permanence of their position therein against accidental displacement, but subject to convenient removal if desired. With these and 25 other objects in view it consists of the following constructions, combinations and arrangements of parts.

In the drawings, Fig. 1 is a central vertical transverse section through a club head 30 embodying my invention. Fig. 2 is a central horizontal section of the same partly in elevation. Fig. 3 is a side elevation of the front or striking face of said club head. Fig. 4 is a modified form of the hereinafter 35 described bolt head or striking head embodied in said invention. Fig. 5 is a rear, or following side elevation of said club head. Fig. 6 is a modified form of the hereinafter 40 described rear weight or insert. Fig. 7 is a top plan view partly in section of a modified form of the hereinafter described bolt.

In the drawings, 1 is the body portion of a golf club of any suitable form or material, preferably of wood, provided with an operating shaft or handle of any suitable construction, a portion of which is shown at 1^a. Said body portion is also preferably provided on its bottom face with a wear shoe 1^b of any suitable construction. 45 Extending transversely through said body portion from the front to the rear faces thereof is a combined weighting, balancing and striking bolt embodying novel features and comprising a striking head member 2, a rear weight member 3, an internally 50 threaded traction screw 4 connected to one

of said members, and an externally threaded traction screw 5 extending through the other of said members into threaded engagement with said internally threaded screw, by means of which traction members the striking head and the rear weight may be drawn toward each other and tightly into recesses provided for them in said body portion and be there retained. Said striking head is preferably provided with a plurality of shoulders as 2^a, 2^b and 2^c, of any desired member, whereby greater depth of solid metal may be secured at the striking center of the head than at the periphery, thus providing density where it is most required without making the entire head too heavy. Either or both of said shoulders 2^b 2^c may, if desired, be omitted within the spirit and scope of certain of my claims. 75 A short space α is preferably left opposite the free end of said internally threaded traction member to permit of taking up any play of said striking head or rear weight which might result from shrinking of the 80 wood.

Further, the striking head and the following weight may have recesses formed in any suitable positions therein, as at 2^d, 3^a in the modified forms thereof (Figs. 4 and 6, respectively), to receive fillers of metal for correcting the balance. That is, when the recesses are empty, the weights may be balanced around their central axes, and if it is desired to have more weight on one side 90 of the central axis, the recess on that side may be filled. If desired, said recesses may be filled with lead or other comparatively heavy material at opposite sides of the axis, merely to increase the weight without changing the balance. The internally threaded traction member may also be partly filled with a greater or less volume of inserted weighting material beyond the inward end of the externally threaded traction member, 95 as with solid lead or lead discs, 6, or shot held in position by a wad interposed, 7, between the said discs and the inward end of said externally threaded screw (Fig. 7). Or if desired, the inward end of the bore 100 of the internally threaded traction member may be plugged with cork or other light substance, followed by lead discs or other suitable weighting substance between said cork and the inward end of said externally 105 threaded screw, thus throwing the additional weight forward or backward in said trac-

tion member as desired, it being understood that variations in growing conditions, age, and seasoning of the wood bodies and slight variations in contours or dimensions of club heads made of the same variety of wood and approximately of the same dimensions tends to produce variations in balance which make compensating adjustments of the weights highly desirable. It appears further that by the long and very rapid swing of the club through the air, any slight defect in balance is accentuated in effect by the long and rapid swing of the club through the air, in a manner more or less similar to the effect on a vessel caused by faulty trim or by a biased helm. It is desirable that the finer adjustments of said weights shall be made by the user of the club, or by professional club makers after the individual club has been tried out by its owner. The importance of the adaptability of my invention for such adjustments will therefore be obvious. The striking head and rear weight may be of any suitable or desired contours or shapes respectively. It will be further obvious that my said invention may be modified in various particulars within the spirit and scope of certain of my claims.

What I claim is:

1. In a golf club, the combination of a club head body portion, a striking head member inserted in the front face thereof, a rear weight inserted in the rear face thereof, an internally threaded traction member attached to one of said members and extending toward the other of said members, an externally threaded traction member extending through said other of said members and into engagement with said internally threaded member, whereby said striking head and said rear weight may be drawn toward each other and tightly into the recesses into which they are inserted.

2. In a golf club the combination of a club head body portion, a striking head member inserted tightly into a concentric recess formed in the front face of said body portion, said striking head having an inwardly directed concentric reduced portion formed thereon, a rear weight tightly inserted in a concentric recess formed in the rear face of said body portion, an internally threaded traction member attached to one of said members and extending toward the other of said members, and an externally threaded traction member extending through said other of said members and into engagement with said internally threaded member.

3. In a golf club, the combination of a club head body portion, a striking weight member inserted in the front face thereof, a rear weight member inserted in the rear

face of said body portion, an internally threaded traction member attached at one end to one of said members and extending through said body portion toward said rear weight member, an externally threaded traction member extending through the other of said weight members and into engagement with said internally threaded member. 65 70

4. In a golf club, the combination of a club head body portion, a striking weight inserted in the front face thereof, said weight having a recess formed in its covered side, a rear weight inserted in the rear face of said body portion, and traction means for drawing said weights toward each other, said recess being adapted to receive a load insert whereby one side of said striking weight may be made heavier than the other. 75 80

5. In a golf club, the combination with a club head body portion, of a striking weight, a load insert extending into the side of said weight, and means for securing said striking weight in said body portion. 85

6. In a golf club, the combination with a club head body portion, of a weight inserted in the rear face thereof, said weight having a recess formed in one of its sides adapted to receive a load insert, and means for holding said rear weight in said body portion. 90

7. In a golf club, the combination of a club head body portion, a striking weight member inserted in the front face thereof, a rear weight inserted in the rear face of said body portion, traction means comprising an internally threaded and an externally threaded member for drawing said weights toward each other, and a separate weight inserted in said internally threaded member in advance of said externally threaded member. 95 100 105

8. In a golf club, the combination with a club head body portion, of a striking weight member inserted in the front face thereof, a rear weight member inserted in the rear face of said body portion, a two-part traction member extending through one of said weights and attached to the other of said weights, and a separate loading element inserted in one of said members. 110

9. In a golf club, the combination with a club head body portion, of a striking weight member inserted in the front face thereof, a rear weight member inserted in the rear face of said body portion, a two-part traction member extending through one of said weights and attached to the other of said weights, and separate loading elements inserted in a plurality of said members. 115 120

In testimony whereof, I hereunto affix my signature.

JOSEPH A. DAHLMAN.
